UNITED STATES PATENT OFFICE.

WILLIAM A. DEMPSEY, OF SCRANTON, PENNSYLVANIA, ASSIGNOR TO DRAPER CORPORATION, OF HOPEDALE, MASSACHUSETTS, A CORPORATION OF MAINE.

AUTOMATIC FILLING-REPLENISHING LOOM.

1,310,793.

Specification of Letters Patent.

Patented July 22, 1919.

Application filed August 19, 1918. Serial No. 250,450.

To all whom it may concern:

Be it known that I, WILLIAM A. DEMPSEY, a citizen of the United States, and resident of Scranton, county of Lackawanna, State of Pennsylvania, have invented an Improvement in Automatic Filling-Replenishing Looms, of which the following description, in connection with the accompanying drawing, is a specification, like characters on the 10 drawing representing like parts.

This invention relates to improvements in filling replenishing looms and the object thereof is to provide means for preventing the severed filling ends from lodging in the 15 bearings of the take-up or sand roll or the guide rolls adjacent thereto which direct the web of cloth.

In automatic filling replenishing looms of the Northrop type in which upon substantial exhaustion of filling upon the filling carrier in the running shuttle a new filling carrier is thrust into and an old filling carrier discharged from the shuttle the filling is engaged by the cutter and clamp of the 20 shuttle feeler which severs the filling and then moves forward carrying the filling end into the path of the temple thread cutter which thereafter cuts the filling end close to the edge or selvage of the web of cloth. 25 The filling end thus severed is then released and drops to the floor or to a suitable receptacle.

Frequently however the severed filling end, particularly when hard twisted yarn 30 which kinks readily is being used, snaps, floats or falls into the bearing of the take-up or sand roll or into the bearing of the guide rolls adjacent which direct the web of cloth. The accumulation of threads thus 35 lodged in the bearings of the take-up or guide rolls becomes wound around the shafts of said rolls and produces a heavy friction against the rotation of the rolls and eventually jams the rolls. The removal of such 40 an accumulation of yarn is difficult and requires considerable time. Furthermore, the filling ends thus caught in the bearings of the rolls accumulate considerable grease and in removing them the workman is likely to 45 inadvertently transfer some of this grease to the web of cloth.

The present invention therefore contemplates the provision of guarding means which will prevent the severed filling ends 50 from becoming lodged in the bearings of the

rolls or in the gears which operate the take-up or sand roll.

Other objects and features of the invention will more fully appear from the following description and accompanying drawings 60 and will be pointed out in the annexed claims.

In the drawings:

Figure 1 is a plan view of a sufficient portion of the end of a loom of the well known 65 Northrop type to illustrate my invention applied thereto,

Fig. 2 is a vertical transverse sectional view through the breast beam, and the take-up, guide and cloth roll,

Fig. 3 is a detail plan view showing my invention overlying the end and bearing of the take-up and guide rolls,

Fig. 4 is a side view of parts corresponding to those illustrated in Fig. 3, and,

Fig. 5 is a detail sectional view illustrating the manner in which the guard embodying my invention is secured to the breast beam of the loom.

My invention is illustrated herein as applied to the well known type of Northrop automatic filling replenishing loom, a sufficient portion of the battery end of which is shown in Fig. 1 to illustrate the manner in which my invention is associated therewith. 80 The parts of the loom thus illustrated comprise the lay 1 having at its end the shuttle box 2 adapted to receive the usual shuttle, a rotary hopper 3 adapted to carry a circular series of fresh filling carriers, which are 85 transferred to the running shuttle by the transfeerer 4 which is controlled by a controller shaft 5 and actuated by the usual bunter mechanism not shown. The invention is more particularly adapted for use in 90 an automatic loom wherein replenishment takes place prior to complete exhaustion and preferably, therefore, the controller shaft 5 is actuated in the usual manner by feeler mechanism and weft fork mechanism. 100 The loom is also provided with a shuttle feeler 6 having thread cutting and clamping devices 7, 8, said shuttle feeler being normally withheld from action by an arm 9 secured to the controller shaft 5 and overlying a stud 10 upon the arm of the shuttle feeler.

The thread cutting and clamping devices of the shuttle feeler are actuated by the usual cam 11 carried by an arm 12 mounted 110

in the usual manner. If desired the loom may be provided with a thread catcher 13 of the type illustrated in Patent No. 683,423 granted September 24, 1901 although by my 5 invention the use of such a thread catcher may readily be dispensed with.

The loom illustrated herein also comprises the usual temple thread cutter 14 carried by an arm 15 slidably mounted in a stand 16 10 secured to the breast beam in the usual manner.

The take-up or sand roll 17 is journaled in suitable bearings 18 in the loom side (see Fig. 2) and desirably is provided with a 15 gear 19 extending about the periphery of said roll through which rotation may be transmitted to it. The loom is also provided with one or more suitable guide rolls, adjacent the take-up roll to direct the cloth, such 20 as the guide roll 20 which is carried in a crescent-shaped bearing 21 at the end of a bracket 22 projecting rearwardly from the front portion of the loom frame. The web of cloth 23 is carried either directly or indirectly 25 over the take-up or sand roll, thence around the guide roll 20 and is finally wound upon the cloth roll 24, which is located beneath the take-up or sand roll in the usual manner.

30. The loom construction thus described is one of the usual types of Northrop loom but it will be understood that my invention is equally applicable to other types. When in the operation of the loom transfer is called 35 for, the shuttle feeler 6 with its attached thread cutter and clamp is advanced and the end of the filling running from the fell of the cloth to the shuttle is clamped and severed in the usual manner adjacent the shuttle 40 eye. As transfer takes place the shuttle feeler rocks forward into its normal position carrying with it the clamped end of the filling. As the filling end is thus drawn forward the portion of it adjacent the fell is 45 drawn into the temple thread cutter in position to be severed by the latter upon the next beat-up of the lay.

When the filling end has thus been severed by the temple thread cutter adjacent 50 the selvage of the cloth a short piece of loose filling is left either hanging to the clamp of the shuttle feeler or in the thread catcher 13 if such a device is used. The clamped end of this thread is released upon 55 the next backward movement of the shuttle feeler and dropped, or if engaged by a thread catcher, is eventually dropped. In either case this loose piece of filling end, particularly if of a kinky nature, is likely 60 to snap or float off so as to become lodged either in the gearing or bearing of the take-up roll or of a guide roll or possibly of the cloth roll itself, and as before stated, where an accumulation of such threads is wound 65 about the shafts of the rolls adjacent their

bearings a great amount of friction is imposed which interferes with the proper action of the take-up roll and at times results in an uneven weave of cloth. Furthermore the friction thus imposed upon the shaft of 70 the take-up roll requires considerably more power to operate the loom.

The present invention contemplates obviating these defects by providing a guard 75 which will overlie the bearings of the take-up roll and guide roll so as to divert any loose filling end which may be dropped and thereby prevent its becoming entangled in the bearing of any of the rolls above mentioned.

A preferred embodiment of my invention which is illustrated herein comprises a plate 80 25 of generally cylindrical contour adapted to overlie the end of the take-up roll 17, its bearing 18 and gear 19 and also to overlie 85 the bearing 21 of the guide roll 20.

The cylindrical curved plate 25 may be provided with an aperture 26 to receive and substantially to fit over the end of the crescent-shaped bearing 21 for the guide roll 20. 90 The guard plate 25 is provided with an offset flat extension 27 adapted to rest upon the breast beam and provided with a longitudinal slot 28 to receive a bolt 29 extending through the breast beam by means of which 95 said plate may be adjustably secured in place.

The bolt 29 thus utilized may be one which is adapted to secure the fork mechanism to the breast beam where a double fork mechanism is used.

In order to insure covering of the bearing of the take-up roll the guard plate 25 is provided with an extension 30 which forms a substantial continuation of the cylindrically curved portion thereof and extends preferably over the middle of the end of the take-up roll.

The extensions 27 and 30 preferably are integral with the plate 25 and are separated 110 by a kerf 31 which enables the extension 27 to be offset in the manner above described.

In order to insure the discharge of any loose filling end which may lodge upon the surface of the guard plate 25 the extension 115 30 may be and desirably is provided with a downwardly turned end 32 which rests in the path of the peripheral gear 19 on the end of the take-up roll and thus effects vibration of the guard plate as the take-up 120 roll rotates.

It will be readily understood that the guard 25 thus located will prevent any possibility of the filling end which is severed at one end by the cutter upon the shuttle 125 feeler and at the other end by the temple thread cutter from being carried into the bearing of any of the rolls or any gearing which actuates said rolls, thereby avoiding all of the objections heretofore mentioned.

It will be understood that the embodiment of the invention disclosed herein is illustrative and not restrictive and that various modifications may be made within the meaning and scope of the following claims.

Having thus described my invention what I claim as new and desire to secure by Letters Patent is:

1. In a loom comprising weaving mechanism and including a take-up roll and means for severing the filling beyond the edge of the web of cloth, means for preventing filling ends thus severed from lodging upon the bearing of said take-up roll including a guard plate overlying the end of said roll and adapted to deflect the falling severed ends away from said bearing.
2. In a loom comprising weaving mechanism and including cloth, take-up and guide rolls and means for severing the filling beyond the edge of the web of cloth, means for preventing the filling ends thus severed from being carried into the bearings of said rolls including a vibratory guard plate positioned to deflect the falling severed ends away from said bearings.
3. In a loom comprising weaving mechanism including cloth, take-up and guide rolls, and means for severing the filling beyond the edge of the web of cloth, means for preventing the filling ends thus severed from being carried into the bearings of said rolls comprising a curved plate overlying the ends of the said rolls and having an extension secured to the breast beam.
4. In a loom comprising weaving mechanism including cloth, take-up and guide rolls, and means for severing the filling beyond the edge of the web of cloth, a curved plate overlying the ends of said take-up and guide rolls and recessed to receive a portion of a guide roll journal and having

an extension secured to the breast beam whereby the severed ends of filling will be prevented from being carried into the bearings of said rolls.

5. In a filling replenishing loom comprising weaving mechanism and including a cloth roll, a take-up roll having a peripheral gear at its end adjacent the battery end of the loom and means for severing the ends of filling beyond the edge of the web of cloth, means for preventing filling ends from being carried into said gear or the bearings of said take-up roll including a guard plate curved cylindrically to conform substantially to the contour of said take-up roll and having extensions, one of said extensions being offset and secured to the breast beam and the other extension provided with a flange engaging the teeth upon said peripheral gear whereby said guard will be vibrated by the rotation of the take-up roll and filling ends which may have lodged upon it shaken off.

6. A guard for the bearing of the take-up roll of a loom comprising a plate cylindrically curved to conform substantially to the contour of the take-up roll and having an offset extension adapted to be secured to a stationary part of the loom.

7. A guard for the bearing of the take-up roll of a loom comprising a plate cylindrically curved to conform substantially to the contour of the take-up roll and having separated extensions, one offset and slotted to provide means of attachment to a stationary portion of the loom and the other of said extensions provided with a flange adapted to rest upon the peripheral gear of the take-up roll.

In testimony whereof, I have signed my name to this specification.

WILLIAM A. DEMPSEY.
